Company, Cleveland, Ohio, a corporation of
Ohio

Application January 11, 1945, Serial No. 572,387

7 Claims. (Cl. 277—60)

1

This invention relates to flow regulating devices and more particularly to devices for automatically maintaining a relatively constant rate of liquid flow irrespective of pressure. In a specific embodiment the apparatus is intended for providing relatively uniform lowering of a hydraulic hoist or like devices which rate is independent of the load on the hoist.

It is a general object of the present invention to provide a novel and improved flow regulator for liquids.

More particularly it is an object of the present invention to provide a flow regulator to be inserted between a hydraulic hoist and the control valve for operating the same and which is arranged to control the return of liquid from the hoist to the valve at a relatively uniform rate independent of the load on the hoist and consequently the pressure of the returning liquid.

An important feature of the invention comprises the serial arrangement of a fixed and a variable flow restricter, the former providing the changes in pressure for the operation of the latter.

Another important feature of the invention consists in the arrangement of a device of the character described to include a passage extending between a port connected to the hoist and a port connected to the operating valve which passage is equipped with a semi-fixed orifice type restricter and an automatic adjustable restricter, the latter comprising a plunger operative in the portion of the path and having a head exposed to the pressure between the two restricters for the automatic operation of the plunger.

A further feature of the invention and illustrated in two embodiments thereof comprises the arrangement of a parallel path between said ports including a check valve permitting maximum flow from the control valve to the hoist but preventing return flow except through the controlled path.

Other and further features and objects of the invention will be more apparent to those skilled in the art upon a consideration of the accompanying drawings and following specification wherein are disclosed exemplary embodiments of the invention with the understanding that such changes, modifications and combinations thereof may be made as fall within the scope of the ap-

10 pended claims without departing from the spirit of the invention.

In said drawings:

Fig. 1 is a longitudinal section through a flow regulating device constructed in accordance with one embodiment of this invention;

Fig. 2 is a view similar to Fig. 1 of a second embodiment providing a different arrangement of the check valve;

Fig. 3 is a schematic or flow sheet illustration of the circuit arrangement of a double acting hoist with a flow control device of the present invention positioned to regulate the rate of lowering of the same, and

Fig. 4 is a view similar to Fig. 3 but illustrating a single acting hoist.

Where hydraulic cylinders are used for the hoisting of loads many occasions require careful control of the lowering operation because of variable loads occurring on the hoist from time to time. Where the load is always the same the rate can be determined by a fixed orifice type of restricter which regulates the rate of liquid return from the underside of the hoist to the reservoir.

Where wide ranges occur in the size of the load this system cannot be resorted to and heretofore the operator has endeavored, by the manipulation of the manual control valve, to obtain some form of control, but most of these control valves are not arranged to provide accurate control because their sensitivity is not sufficiently great. This results from a relatively short movement between fully open and fully closed positions.

In accordance with the present invention a flow regulator is provided, arranged to be inserted between the hoist and the control valve, which provides automatically for maintaining a predetermined rate of lowering which does not vary substantially from no load to maximum load. This rate may be regulated in a simple manner and thereafter remains constant.

Fig. 3 illustrates a conventional circuit for the operation of a double acting hydraulic hoist 10, which comprises a cylinder having a piston 11 which can be lifted by introducing pressure liquid beneath it and lowered by introducing pressure liquid above it while drawing out the liquid from beneath. Liquid under pressure is provided by pump 12, receiving its supply from reservoir 14, and delivering liquid either to the underside or

2

upper side of the piston under the selective control of the manually operated control valve 15. When liquid under pressure is delivered to one side of the hoist the other side discharges its liquid back through the valve 15 to the reservoir.

In order to regulate the rate at which the liquid is discharged from beneath the piston so as to maintain a substantially uniform hoist lowering rate independent of the load connected to the piston rod 16 thereof, the flow control device 20 of the present invention is introduced in the pipe line 21 between the lower side of the hoist and the control valve. In Fig. 4 the flow control device 20 is identical and so are all of the other parts except the hoist which is of the so called single acting type. Here the weight on the piston rod 16 is relied on for lowering the hoist and no fluid is introduced above the piston for the purpose. The manual valve for controlling the operation of the hoist is shown at 22 and is somewhat simpler than that shown in Fig. 3 at 15 for controlling the double acting hoist.

Referring to Fig. 1 for an understanding of the flow control device, it will be seen to comprise a suitably cast housing 24 having a first or hoist port 25 adapted for connection to the lower side of the hoist cylinder and a second or control valve port 26 for connection to the manually operated control valve for the hoist. The first of these ports opens into a duct 27 which connects by a horizontal connection 28 with a parallel duct 29. The second port opens into a chamber 30 at the right end of the housing. A further chamber 31 appears at the left end of the housing. Both of these chambers and the parallel ducts are intersected by a horizontal cylindrical bore 32, plugged at the left end by a screw plug 33 having a stop lug 34 thereon, and plugged at the right end by a screw plug 35 having a spring receiving cup 36 on its inner end.

The bore 32 mounts for reciprocation, through a small range, a restricter plunger 38 normally positioned with its left end against the stop lug 34 under the action of a spring 40 surrounding a projection 41 on the right end of the plunger and supported between it and the cup 36.

A duct 42 projects downwardly from chamber 31 and a corresponding duct 43 projects downwardly from chamber 30 and the two are connected by horizontal duct 44. An enlarged bore 45 coaxial with 44 extends to the right surface of the housing and the inner end supports a non-circular portion 47 of a restricter plug having a long tapered end 50 movable into the duct 44 to regulate the orifice between it and duct 43. The position of this restricter plug 50 is manually adjusted by means of a threaded rod 51 engaged in a plug 52 closing the right end of bore 45. This threaded rod has a reduced end received in a socket in the part 47. Suitable lock and cap nuts, as shown, serve to maintain the adjustment of the rod 51 and to prevent leakage.

The plunger 38 has a small bore 55 extending to near its right hand end and a larger or counter-bore 56 extending through its left end and closed by plug 57 whose inner end provides a spring centering pin 58. A check valve plunger 59 has a skirt 60 slideable in counter-bore 56 and receiving the right end of spring 61, the left end of which is mounted on pin 58. The tapered right end of the valve plunger 59 seats at the junction of the bore and counter-bore.

The inner end of bore 55 connects by radial

passages 63 to chamber 30 in all positions of the plunger. The end of the counter-bore 56 positioned to the right of the skirt 60 of the check valve plunger connects at all times by radial bores 65 to the duct 29. The extreme left end of the counter-bore 56 connects by radial passages 66 to the chamber 31 in all positions of the valve plunger.

A plurality of staggered radial passages 68 extend from an intermediate portion of the counter-bore 56 into duct 27 and are so arranged that they are successively eclipsed by the walls of the bore 32 as the plunger is moved towards the right.

15 In operation the flow control device is connected as shown in Fig. 3 and when fluid is introduced through port 26 to lift the hoist it follows two parallel passages to hoist port 25. The first of these includes port 26, chamber 30, 20 radial passages 63, plunger bore 55 where it lifts check valve plunger 59, flows into the right end of counter-bore 56, outwardly through radial passages 65 into duct 29, through connecting horizontal duct 28, then to duct 27 and hence 25 to hoist port 25. Duct 27 is enlarged so that the fluid flows circumferentially around the outside of plunger 38 in moving from 28 to 25.

This passage just described carries the major portion of the liquid for operating the hoist. 30 A second passage, however, carries some of the liquid as follows: port 26, chamber 30, vertical duct 43, orifice controlled by 50, duct 44, vertical duct 42, chamber 31, radial passages 66, counter-bore 56, staggered radial passages 68, duct 27 and port 25.

When the operator manipulates the control valve to lower the hoist, the chamber beneath the piston is connected to the reservoir and fluid then begins to flow into port 25 of the device of 40 Fig. 1, enters duct 27 and passages 68 to counter-bore 56, where it immediately closes check valve plunger 59, assisted by its spring. Liquid then flows out through radial ports 66 into chamber 31, into vertical duct 42, connecting horizontal duct 44, vertical duct 43, chamber 30 and port 26. With no load on the hoist, the adjusting screw 51 is manipulated to initially regulate the orifice controlled by the conical member 50 to provide the desired rate of lowering for the hoist. This no-load rate then automatically becomes the rate at which the hoist is lowered under any condition of loading because of the action now about to be explained.

It will be noted that the right head of valve 55 plunger 38 is exposed to the low pressure existing in chamber 30 because of its connection to reservoir 14 during the lowering operation. The left head of plunger 38, however, is exposed to pressure in the chamber 31, and this pressure tends to increase as the load on the hoist is increased because of the restriction to flow caused by means of the orifice controlled by 50. This pressure on the left head of the plunger moves it toward the right against the action of its spring 40 to progressively reduce the total of the exposed areas of the staggered passages 68 so that the quantity of oil permitted to flow to chamber 31 is reduced to the quantity which can pass through the orifice controlled by the conical member 50 at the rate at which it would flow under no load conditions of the hoist. Whatever the load on the hoist the plunger 38 assumes such a position that the flow of liquid is restricted thereby to the quantity which can flow through the semi-permanent restricter

at 50 at a predetermined velocity. This condition exists because the left end of the valve plunger is exposed in the fluid in the passage between the fixed restricter and the variable restricter. When the hoist is first started on its lowering movement there may be some slight oscillation of the plunger 38, but this soon finds its optimum position and regulates the lowering of the hoist at the rate predetermined by the setting of the semi-fixed restricter 50.

The check valve 56 is for convenience incorporated in the plunger of Fig. 1 where it simplifies to some extent the machining operations. It need not, however, be so located and in Fig. 2 it is illustrated as positioned in a stationary portion of the housing.

In this figure the parts in general are the same as in Fig. 1 and the operation is the same. The only differences occur in the positioning of the check valve and hence slightly in the arrangement of the main plunger. In this case the plunger 38' is bored from the right end as at 55' where a closure plug provides a stud for supporting the spring. Radial bores 63' provide for fluid access from chamber 30' and radial bores 65' permit egress into a vertical duct 70 connected by a horizontal duct 28' with vertical duct 27' leading to hoist port 25'.

A threaded vertical bore 72 in the top of the housing between the two main ports accommodates a screw plug 73 centrally bored to provide sliding fit for a check valve plunger 74 and its spring 75. The end of the plunger seats in the duct 70.

The left end of plunger 38' is bored as at 56' and functions as before described.

In this valve the operation in lowering is identical with that described in connection with Fig. 1 but on raising the path of the liquid via the check valve is as follows: port 26', chamber 30', passages 63', valve plunger bore 55', radial ports 65', duct 70 to lift check valve 74, duct 28' and port 25'.

Both of the embodiments of the invention are extremely simple in construction and are thoroughly reliable in operation. They materially simplify the work of the operator who does not have to endeavor to manipulate his control valve to regulate the rate of lowering of the hoist. The valve of the present invention can be constructed as an independent unit as illustrated or it may be combined with the control valve in an obvious fashion.

I claim:

1. A flow regulating device for connection between a hydraulic hoist and the control valve therefor and adapted to maintain a substantially uniform lowering rate for the hoist while permitting a variable lift rate, comprising in combination, a housing having a first or hoist port and a second or control valve port, two passages connecting said ports and providing parallel flow paths therebetween, a semi-fixed orifice-type restriction in one of said paths, a check valve in the second path open only to flow from the second port to the first, a valve type restricter including a hollow plunger in the first path between the first port and the first mentioned restricter and having a radial orifice communicating with the first port and a second radial orifice communicating with the said first restricter, a spring normally maintaining the plunger so that the said passages are fully open, means adapted to provide pressure unbalance on the said plunger to move it against the spring to restrict one of

said orifices and hence the first passage when the pressure at the first port increases, said check valve being arranged within the hollow of said plunger and having one end thereof exposed through said plunger to the control valve port and the other end exposed through said plunger to the hoist port.

2. A flow regulating device for connection between a hydraulic hoist and the control valve therefor and adapted to maintain a substantially uniform lowering rate for the hoist while permitting a variable lift rate, comprising in combination, a housing having a first or hoist port and a second or control valve port, two passages connecting said ports and providing parallel flow paths therebetween, a semi-fixed orifice-type restriction in one of said paths, a check valve in the second path open only to flow from the second port to the first, a variable restricter on the first port side of the orifice type restricter, said variable restricter being constructed as a hollow tubular plunger parted and arranged to be pressure moved to automatically restrict the flow through the first passage to a quantity equal to that which will pass the orifice-type restricter at minimum lowering pressure, both of said passages extending longitudinally through said plunger and a spring to normally maintain the plunger in a position of minimum restriction.

3. A flow regulator for connection between a hydraulic hoist and a control valve therefor adapted to provide uniform lowering speed irrespective of load comprising in combination, a housing having a hoist port and a valve port, a chamber at each end of said housing, one being connected to the valve port, a bore connecting said chambers, a plunger reciprocably mounted in said bore and having one end in each chamber, a duct also connecting said chambers, a flow restricter in said duct, a pocket connected to the hoist port and intersecting said bore, a longitudinal tunnel extending in said plunger, an opening connecting the tunnel to the chamber which is not connected to the valve port, an opening from the tunnel to said pocket, one of said openings being positioned to be progressively eclipsed by the walls of the bore as the plunger is moved toward the chamber connected to the control valve port, and a spring opposing such movement of the plunger.

4. A flow regulator of the type described comprising in combination, a housing having a hoist port and a control valve port, a pair of spaced chambers in the housing, one being connected to the valve port, a bore connecting said chambers, a tubular plunger reciprocably mounted in said bore, having one end in and open to the valve port connected chamber, a duct also connecting said chambers and providing a flow restriction, a pocket connected to said hoist port and intersecting said bore, an opening through the plunger wall connecting its interior to said pocket, a second opening in the plunger wall connecting its interior to the other chamber, a spring biasing the plunger toward the last mentioned chamber, at least one of said plunger wall openings being positioned to be gradually eclipsed by a wall of the bore as the plunger is moved against said bias to restrict the flow from the pocket to the second chamber and a check valve in said plunger separating the open end thereof from the wall opening leading to the pocket and opening towards the pocket.

5. A flow regulator of the type described comprising in combination, a housing having spaced

chambers and an intermediate pocket, a hoist port for said pocket and a control valve port for one of said chambers, a bore connecting said chambers and pocket, a tubular plunger reciprocably mounted in said bore with its ends in the chambers and biased toward the unported one, a duct connecting said chambers and having a semi-permanent flow restrictor, the hollow center of the plunger being permanently in free communication with the ported chamber, the hollow center of the plunger being in communication with the other chamber and with the pocket, a check valve wholly housed in said plunger and separating said last mentioned communication from the first whereby the plunger hollow is divided into two parts arranged for flow only from the first communication to the last and means to eclipse at least one of the last two communications as the valve plunger is moved against the bias by excess pressure in the unported chamber due to flow through the plunger from the pocket.

6. A flow regulator as defined in claim 3 in which the tunnel is open to the chamber connected to the valve port, and a check valve is arranged in the tunnel to permit flow from the port connected chamber to the pocket but not vice versa.

7. A flow regulator of the type described comprising in combination, a housing having spaced chambers and an intermediate pocket, a hoist port for said pocket and a control port for one of said chambers, a bore extending from chamber to chamber and through said pocket, a hollow plunger reciprocably mounted in said bore with

5
10
15

ends extending into each chamber, means biasing the plunger toward the unported chamber, a duct connecting said chambers and having an adjustable flow regulator therein, a check valve separating the plunger hollow into an inlet and a discharge compartment, means placing said inlet compartment always in communication with the ported chamber, means placing the outlet compartment in communication with the remaining chamber and means placing the outlet compartment into communication with said pocket, at least one of said last two means being positioned to be progressively eclipsed by walls of said bore as the plunger is moved against said bias by pressure in the unported chamber.
